UNITED STATES PATENT OFFICE.

AUGUSTUS F. PRIEST, OF CHICAGO, ILLINOIS.

CARBURETER.

1,307,374.

Specification of Letters Patent. Patented June 24, 1919.

Application filed March 4, 1918. Serial No. 220,262.

To all whom it may concern:

Be it known that I, AUGUSTUS F. PRIEST, a citizen of the United States, residing at Chicago, in the county of Cook and State of Illinois, have invented certain new and useful Improvements in Carbureters.

My invention relates to means for introducing air into the combustible mixture at the outlet of a carbureter and varying the amount of air so introduced to correspond with the varying requirements upon the carbureter.

The object of my invention is to produce a simple, efficient and thoroughly reliable device of the kind described whereby the operation of the throttle or mixture discharge controlling valve of the carbureter will automatically control the admission of air to the mixture as it escapes from the carbureter.

To this end my invention consists in the novel construction, arrangement and combination of parts herein shown and described and more particularly pointed out in the claims.

In the accompanying drawings wherein like or similar reference characters indicate like or corresponding parts:

Figure 1 is a top plan view of a carbureter equipped with my improvement.

Fig. 2 is a fragmentary side elevation of the same.

Fig. 3 is a section taken substantially on line 3-3 of Fig. 1.

Fig. 4 is a section taken substantially on line 4-4 of Fig. 2.

Fig. 5 is a section taken substantially on the plane of one face of the carbureter throttle or discharge controlling valve showing the preferred form of valve plate and associated portions of the valve stem.

Fig. 6 is a view similar to Fig. 4 but showing the throttle valve substantially in its wide open position.

Fig. 7 is a view similar to Fig. 1 showing a modified form of my device.

Fig. 8 is a view similar to Fig. 2 but showing the modification shown in Fig. 7.

Fig. 9 is a section taken substantially on line 9-9 of Fig. 8.

In the drawings I have shown my improvement applied to an ordinary form of carbureter 1 having an air inlet 2 and mixture outlet 3 in substantially the usual manner with a flange 4 at the outlet for attaching the carbureter to the intake manifold of

an internal combustion motor. As shown my improvement comprises a butter-fly valve of the usual or any preferred form having a valve plate 5 adapted to close the outlet opening of the carbureter rigidly attached to a tubular stem 6 extending centrally through the outlet opening and provided with a lever 7 at the exterior of the carbureter for oscillating the stem to control the position of the valve plate. As shown the ends of the valve stem 6 are closed and an opening 8 is formed through the side wall of the stem within the outlet 3 of the carbureter at the outer face of the valve plate 5 at substantially right angles thereto. In the form shown a part 9 is rotatably mounted upon the valve stem 6 between the hub 24 of the lever 7 and the boss 10 upon the carbureter inclosing the stem. As shown the part 9 is provided with a stirrup 11 at one end adapted to snugly fit a pin 12 projecting from the carbureter near the boss 10 adapted to rigidly maintain the part 9 in position upon the carbureter. A lateral projection 14 is also provided upon the part 9, said projection having a port 15 (see Fig. 4) extending longitudinally thereof with its inner end registering with a lateral opening 16 in the valve stem 6. The outer end of the part 15 is preferably provided with an angular part 17 at its outer end open at one edge of the part 9 so that air may enter the carbureter outlet by passing through the port 17-15 thence through the opening 16 and the bore of the valve stem 6 and thence escape into the carbureter outlet through the opening 8 in the valve stem. The several parts are so positioned and arranged that when the valve plate 5 is positioned to partially open the outlet opening of the carbureter the opening 16 and passage 17 will be fully open thus permitting the maximum amount of air to pass into the outlet opening. As the valve plate 5 is moved however toward the fully open position the part 9 gradually covers the opening 16 until it is substantially closed when the valve arrives at its fully open position as shown in Fig. 6.

Any suitable means may be provided to close the outer end of the port 15-17 when the valve approaches its closed position. As shown the lever 7 is provided with a lateral extension 18 having a suitably formed socket 19 formed near the end thereof and a plunger 20 is positioned in the socket 19 having a tapering end 21 adapt-

- ed to engage and close the outer end of the passage 15-17. As shown the plunger 20 is movable longitudinally of the socket and a spring 22 is provided adapted to normally hold the plunger 20 at the outer limit of its movement as shown in Fig. 4 so that as the lever is moved to close the outlet opening the plunger 20 engages the outer end of the passage 15-17 and closes the same 5
- 10 when the valve is in position for permitting sufficient mixture to pass through the carbureter to cause the motor to which it is attached to operate satisfactorily light or idling. When it is desired to further reduce 15 the speed of the motor the lever 7 may be operated to completely close the outlet opening of the carbureter, the spring 22 permitting the plunger 20 to recede into the socket sufficiently to permit this movement 20 of the lever 7 after the plunger 20 has closed the outer end of the passage. In the preferred construction in order to maintain the several parts in position when detached from the carbureter and to insure 25 the accurate engagement of the plunger 20 in the outer end of the passage I have provided a projection 23 upon the part 11 adapted to engage the outer face of the hub 24 of the lever 7 to prevent lateral 30 movement between the lever and the part 9 also permitting the several parts of my improvement to be assembled independently of the remainder of the carbureter when desired. I have also found it desirable 35 to attach the plate and the stem 6 by providing a slotted opening 25 through the stem adapted to snugly fit the plate 5. Suitable lateral openings 26 are also provided through the plate and adjacent 40 portion of the stem to receive a staple 27 or other fastening means adapted to rigidly maintain the plate 5 in position when in service. In order also to secure the full bore of the stem 6 and opening 8 I have 45 provided notches 28-29 in the opposite edges of the plate 5 each adapted to register with the bore of the stem 6 and the opening 8 the opposite halves of the plate being formed symmetrical so that the plate 50 may be inserted in the stem with either the notch 28 or 29 in position to register with the opening 8 and the openings 26 will be in position to receive the arms of the staple 27 to hold the plate 5 in position 55 thus avoiding the possibility of placing the plate 5 in the stem 6 in position to partially close the opening 8 and thus interfere with the operation of my device.
- In the form shown in Figs. 7, 8 and 9 60 the several parts are constructed and arranged substantially the same as hereinbefore described with the exception of the mechanism for preventing the admission of air to the outlet opening of the carbureter 65 when the valve 5 is approaching its closed

position. In this form the part 30 which corresponds to the part 9 in the form hereinbefore described is provided with a substantially straight longitudinal passage 31 extending from the valve stem to its extremity and the end or face 32 of the part 30 is curved transversely to an arc the center of which is at the center of the valve stem. In this form also the part 33 which corresponds to the part 18 in the form hereinbefore described is provided with a substantially flat end and a spring 34 is rigidly secured thereto having a part 35 provided with a broad curved face adapted to snugly fit against the face 32 of the part 30 to close the open end of the passage 31. A projection 36 is provided at the end of the face 32 adjacent the part 33 and the spring 34 is provided with a shoulder 37 adapted to engage the projection 36 when the valve arrives at the point where it is desired to admit air to the outlet so that a further movement of the valve and associated parts will cause the shoulder 37 to coöperate with the projection 36 and suddenly force the part 35 of the spring outward from the face 32 thus fully opening the passage 31 as shown in Fig. 9. The operation in all other respects remains substantially the same as before described.

Having thus described my improvement it is obvious that various immaterial modifications may be made in my device without departing from the spirit of my invention, hence I do not wish to be understood as limiting myself to the exact form or construction shown.

What I claim as new and desire to secure by Letters Patent is:

1. In a carbureter, a butterfly valve adapted to control the mixture outlet of the carbureter, said valve having a tubular stem provided with two openings through its side one of which is at the face of said valve, in combination with a part upon the carbureter having a passage therethrough, one end of said passage being adapted to register with the other opening in said stem when said valve is partially open, and means mounted upon said stem adapted to close the opposite end of said passage when said valve approaches its closed position.
2. In a carbureter, a butterfly valve adapted to control the mixture outlet of the carbureter, said valve having a tubular stem provided with two openings through its side, one of which is at the inner face of said valve, in combination with a part upon the carbureter having a passage therethrough, one end of said passage being adapted to register with the other opening in said stem when said valve is partially open, and means mounted upon said stem adapted to close the opposite end of said passage when said valve approaches its closed position.

3. In a carbureter, a butterfly valve adapted to control the mixture outlet of the carbureter, said valve having a tubular stem provided with two openings through its side 5 one of which is at the face of said valve, in combination with a part rigidly attached to the carbureter having a passage therethrough, one end of said passage being adapted to register with the other opening 10 in said stem when said valve is partially open, and means mounted upon said stem adapted to close the opposite end of said passage when said valve approaches its closed position.
4. In a carbureter, a butterfly valve adapted to control the mixture outlet of the carbureter said valve having a tubular stem provided with two openings through its side one of which is at the face of said valve, in 15 combination with a part rotatably attached to said stem and rigidly attached to said carbureter by said stem and having a passage therethrough, one end of which is adapted to register with the other opening in said stem when said valve is partially open, and means mounted upon said stem adapted to 20 close the opposite end of said passage when said valve approaches its closed position.
5. In a carbureter, a butterfly valve 25 adapted to control the mixture outlet of the carbureter said valve having a tubular stem provided with two openings through its side one of which is at the face of said valve, in combination with a part upon the carbureter 30 having a passage therethrough, one end of said passage being adapted to register with the other opening in said stem when said valve is partially open said opening being gradually closed by said part as said valve 35 approaches its fully open position and means mounted upon said stem adapted to close the opposite end of said passage when said valve approaches its closed position.
6. In a carbureter, a butterfly valve
- adapted to control the mixture outlet of the 45 carbureter, said valve having a tubular stem provided with two openings through its side one of which is at the face of said valve, in combination with a part upon the carbureter having a passage therethrough, one end 50 of said passage being adapted to register with the other opening in said stem when said valve is partially open, and resilient means mounted upon said stem adapted to close the opposite end of said passage when said valve 55 approaches its closed position.
7. In a carbureter, a butterfly valve adapted to control the mixture outlet of the carbureter, said valve having a tubular stem provided with two openings through its side, 60 one of which is at the inner face of said valve, in combination with a part rigidly attached to the carbureter having a passage therethrough one end of said passage being adapted to register with the other opening in 65 said stem when said valve is partially open, and means mounted upon said stem adapted to close the opposite end of said passage when said valve approaches its closed position.
8. In a carbureter, a butterfly valve 70 comprising a stem and a closure plate rigidly attached to said stem, said stem being tubular and having a slot therethrough to receive said plate and an opening through the wall of said stem at the face of said 75 plate, said plate having a pair of notches in its opposite edges each adapted to register with said openings and the central bore of said stem and means for removably attaching said plate to said stem.

In testimony whereof, I have hereunto signed my name in the presence of two subscribing witnesses.
